J. A. CHOQUETTE
FLUID DRIVEN TURBINE

Filed July 5, 1927

JOHN ALBERT CHOQUETTE
INVENTOR.

UNITED STATES PATENT OFFICE.

JOHN ALBERT CHOQUETTE, OF OTTAWA, ONTARIO, CANADA.

FLUID-DRIVEN TURBINE.

Application filed July 5, 1927. Serial No. 203,594.

This invention relates to turbines of the kind comprising a cylindrical casing having diametrically opposed inlet ports through which fluid under pressure is projected tangentially onto the vanes of a rotor mounted in said casing. A turbine of this kind is described in applicant's co-pending application No. 748,404, November 7, 1924, patented March 6, 1928, No. 1,661,716.

10 The object of the invention is to provide certain improvements in turbines of this kind whereby their construction is simplified and their efficiency increased.

The present invention consists in a turbine of the kind described wherein diametrically opposed fluid discharge ports are provided closely adjacent the fluid inlet ports and wherein an inwardly extending projection is provided on the casing between each adjacent pair of inlet and discharge ports, said projections being in substantially fluid-tight contact with or proximity to the rotor and shaped on one side to direct fluid from the inlet ports tangentially onto the vanes of the rotor and on the other side to direct fluid from the vanes into the discharge ports, the outer ends of substantially all the vanes being spaced a uniform distance from the interior surface of the casing except those which contact with said projection, characterized by the provision of vanes on the end walls of the rotor in addition to vanes on the periphery thereof.

Referring now to the accompanying drawings which illustrate by way of example one convenient embodiment of the invention,

Figure 1 is a central, vertical sectional elevation,

Figure 2 is a section on line 2—2 of Figure 1,

Figure 3 is a side elevation and

Figure 4 is a section on line 4—4 of Figure 1.

The casing comprises a hollow cylindrical portion 1 closed by end walls 2 and 3, and at the centre of the casing is a shaft 4 to which a rotor drum 5 is rigidly secured, for example, by means of keys 6. The rotor drum 5 carries on its periphery a series of relatively narrow and closely spaced vanes or blades 7 and a series of similar vanes 8 is carried by each of the end walls of the drum 5.

The outer edges of the vanes 7 and 8 are spaced from the casing a substantial distance throughout the major portion of the circumference of the casing, but at the top and bot-

tom of the casing this space is divided into two parts by means of diametrically arranged projections or baffles 9. The baffles 9 are shaped on their inner surfaces so as to fit in fluid tight contact with the outer edges of the vanes 7 and 9 with a minimum of friction. Adjacent one side of each baffle the casing is provided with a fluid inlet opening 10 and adjacent the opposite side of each baffle is provided a fluid outlet 11.

Diametrically opposed velocity increasing elements or deflectors 12 are arranged in the spaces through which fluid passes from the inlets 10 to the outlets 11. Similar radially disposed deflectors 13, which are connected by the deflectors 12, extend down in proximity to the side vanes 8 and are carried by discs or bosses 14, one of which may be rotatably mounted on a bushing 15 keyed to the casing at 16, while the other may be provided with a central boss 17 keyed at 18 to a bushing 19.

Means are provided for adjusting the position of the deflectors when desired and these means may conveniently take the form of a worm 20 meshing with a worm-wheel 21 keyed at 22 to the boss 17 of the deflector structure 12—13—14.

The side vanes 8 are substantially radial and are preferably arranged to form side continuation of the peripheral vanes 7. The vanes 8 may be made integral with the vanes 7, but are preferably made separately and welded or otherwise connected to the ends of the vanes 7 as indicated at 23, Figure 2.

The construction and operation is similar to that of the turbine described in applicant's British Patent No. 241,907 and Canadian Patent No. 263,287, excepting for the provision of the side vanes 8 which add considerably to the efficiency of the device.

Liquid under a pressure created by a head or a pump is introduced into the inlets 10 and flows slowly at a high pressure through the spaces between the inlets 10 and the deflectors 12—13, and from the deflectors to the outlets 11 the fluid flows at a high velocity, thus causing a rapid rotation of the rotor. The shaft 4 of the rotor is connected to any suitable pulleys or transmission gearing, not shown.

The form of the invention above described is given by way of example only, and may be modified within the scope of the appended claims without departing from the invention.

What I claim is:

1. A turbine comprising a cylindrical cas-

ing having diametrically opposed fluid inlet ports, a rotor mounted concentrically in said casing, a series of vanes on the periphery of said rotor, a series of vanes on each of the end 5 walls of the rotor, diametrically opposed fluid discharge ports closely adjacent said fluid inlet ports, an inwardly extending projection on the casing between each adjacent pair of inlet and discharge ports, said projections 10 being in substantially fluid-tight contact with or proximity to the rotor and shaped on one side to direct fluid from the inlet ports tangentially onto the vanes of the rotor and on the other side to direct fluid from the vanes

into the discharge ports, the outer ends of substantially all the vanes being spaced a uniform distance from the interior surface of the casing except those which contact with said projections, and fluid velocity increasing deflectors coacting with the said peripheral 15 20 vanes and said side vanes.

2. A turbine as claimed in claim 1, wherein means are provided for adjusting the angular position of said velocity increasing members. 25

In testimony whereof I have affixed my signature.

JOHN ALBERT CHOQUETTE.
